UNITED STATES PATENT OFFICE.

ROLPH J. LACKNER, OF OZONE PARK, NEW YORK, ASSIGNOR TO LACKNER PRODUCTS CORPORATION, OF BROOKLYN, NEW YORK, A CORPORATION OF DELAWARE.

DESIGN FOR A COMBINED LIGHT GLOBE AND TRAFFIC SIGNAL.

Application filed April 5, 1928. Serial No. 26,144. Term of patent 14 years.

To all whom it may concern:

Be it known that I, ROLPH J. LACKNER, a citizen of the United States of America, residing at Ozone Park, in the county of Queens and State of New York, have invented a new, original, and ornamental Design for a Combined Light Globe and Traffic Signal, of which the following is a specification, reference being had to the accompanying drawing, forming a part hereof.

In the drawing:

Figure 1 is a side elevation looking at one side of a globe formed in accordance with the new design;

Fig. 2 is a similar view taken at right angles to the view in Fig. 1, and

Fig. 3 is a top plan view of the globe.

I claim:

The ornamental design for a combined light globe and traffic signal, as shown.

ROLPH J. LACKNER. [L.S.]
